UNITED STATES PATENT OFFICE.

FRIEDRICH HASSENPLUG, OF NEW YORK, N. Y.

DESIGN FOR TRIMMING.

SPECIFICATION forming part of Design No. 24,714, dated September 24, 1895.

Application filed August 20, 1895. Serial No. 559,959. Term of patent 7 years.

To all whom it may concern:

Be it known that I, FRIEDRICH HASSEN-
PFLUG, a citizen of the United States, residing
in New York city, in the county and State
5 of New York, have invented and produced a
new and original Design for Trimming, of
which the following is a specification.

Reference is to be had to the accompanying
drawings, forming a part of this specification,
10 in which similar characters of reference in-
dicate corresponding parts in both the fig-
ures.

Figure 1 is a perspective view of the trim-

ming, showing my design; and Fig. 2 is a
cross-section of the same.

The leading feature of my design consists
in a trimming-body formed with wings A, B,
C, D, and E, extending at angles one to the
other and radiating from a common center.

I claim—

The design for a trimming as herein shown
and described.

FRIEDRICH HASSENPLUG.
